UNITED STATES PATENT OFFICE

2,141,873

HEATING APPARATUS

Arthur B. Modine, Racine, Wis., assignor to Modine Manufacturing Company, Racine, Wis., a corporation of Wisconsin

Application August 29, 1936, Serial No. 98,604

3 Claims. (Cl. 126—110)

This invention relates to heating apparatus, and particularly to a device wherein the heat producing and heat exchange elements are combined in a unitary structure.

5 One object of the present invention is to provide a structure of maximum heat exchange capacity, and wherein the products of combustion are drawn through the heat exchange devices by the operation of a novel circulating means acting 10 also to pass currents of air to be heated over the said devices.

Another object of the invention is to provide a structure having a pilot for lighting the main burner, and wherein the supply of fuel to the burner is automatically controlled by the condition 15 of the pilot light and by the temperature conditions existing in the heat exchange devices.

A further object of the invention is to provide a heating apparatus which is compact, highly 20 efficient, of maximum capacity, and wherein the safe and efficient operation of the device is automatically controlled.

A still further object of the invention is to improve devices of the character described in sundry details hereinafter referred to and particularly pointed out in the appended claims.

One embodiment of the present invention is shown for illustrative purposes in the accompanying drawings, in which:

30 Fig. 1 is an elevational view, partly in section, of a heating apparatus embodying features of the present invention;

Fig. 2 is a side elevational view, partly in section, of the structure illustrated in Fig. 1;

35 Fig. 3 is an enlarged fragmentary elevational view partly in section, illustrating the arrangement of a burner, pilot light and a thermal-operated mercury switch in relation thereto and forming a part of the embodiment illustrated in Figs. 1 and 2;

40 Fig. 4 is an enlarged sectional elevational view of the main fuel supply valve illustrating the arrangement of a solenoid for actuating the valve; and

45 Fig. 5 is a diagrammatic view of the structure shown in Figs. 1 to 4, inclusive, and illustrating the arrangement of an electrical circuit employed for automatically controlling the operation of the heating apparatus.

50 The illustrative embodiment of the invention shown in the drawings comprises an elongated housing, indicated as a whole by the numeral 11, having upwardly and inwardly inclined side portions 12, and embodying a combustion chamber 13 in the upper portion thereof, the housing 11

being provided, preferably, adjacent the lower portion of the respective ends thereof with openings 14 and 15 for the admission of air into the combustion chamber, the openings being shown, in the present instance, as provided with a wire screen 16 or other suitable filtering fabric for preventing the admission of dust or other foreign matter into the combustion chamber. 5

Mounted in the chamber 13 and extending longitudinally thereof is a burner, indicated as a whole by the numeral 17, and comprising a plurality of perforated tubes 18, provided with a plurality of perforations 19, preferably, along their upper side portion for the discharge of fuel therefrom. 10

For supplying fuel, such as illuminating gas, for example, to the burner 17, a distributor head 20 is positioned adjacent one end of the tubes 18 in a manner to communicate with the tubes and provide a support therefor, and communicating 20 also with the distributor head 20 is an elongated tubular member 21 providing a mixing chamber and having an open end portion adjacent the opening 15 and one of the screens 16 for the admission of air to the mixing chamber and to receive the fuel nozzle 22 communicating with a fuel supply pipe 23 adapted to be connected to a suitable source of fuel gas supply, as, for example, to a gas main. 25

For controlling the passage of fuel to the nozzle 30 22, the supply pipe 23 is provided with a solenoid valve, indicated as a whole by the numeral 24, and comprising a housing 25 in which is mounted a valve 26 having a stem 27, shown, in the present instance, as extending upwardly therefrom and operatively connected to an electrically operated solenoid 28, by the energizing of which, the valve is forced downwardly against the force exerted by a spring 29 which acts to close the valve 26 when the solenoid 28 is de-energized. 35

For automatically igniting the gas at the burner 17 when the solenoid valve 24 is opened, a pilot light 31 is positioned in the housing 11 in operative relation to the burner and connected by means of the pipe 32 to the supply pipe 23 for 45 bypassing the gas around the main solenoid valve 24, the pipe 32 being provided with a hand operated valve 33 for controlling a supply of gas to the pilot light.

Mounted adjacent the upper end portion of the 50 housing 11 and communicating with the combustion chamber formed therein are a plurality of laterally extending flues 34 shown, in the present instance, as extending in opposite directions from the combustion chamber and having a plu-

rality of heat radiating fins 35 mounted thereon, the outer ends of the oppositely extending flues being provided, respectively, with headers 36 and 37 with which the flues 34 communicate for distribution of the heat and products of combustion from the chamber 13.

Mounted on and communicating with the headers 36 and 37 are a plurality of conduits 38 shown, in the present instance, as extending upwardly therefrom and communicating at their upper ends with a casing 39 having a discharge pipe or opening 41 extending outwardly from the casing by which the products of combustion are discharged into the atmosphere, the casing 39 being shown, in the present instance, as provided with oppositely disposed brackets 42 by which the entire structure may be supported by means of hangers 43 or other suitable means.

Mounted, preferably, on the conduits 38, by means of brackets 44, is an electric motor 45 having a shaft 46 mounted therein, the upper end of the shaft terminating within the housing 39 and being provided therein with a fan 47 for drawing air through the combustion chamber 13 and the products of combustion through the flues 34, headers 36 and 37 and conduits 38 into the casing 39 and discharging them therefrom through the discharge pipe 41, the opposite end of the shaft 46 being provided with an impeller fan 48 for directing currents of air past the headers 36 and 37, flues 34 and the housing 11 comprising the combustion chamber 13, the arrangement being such that the currents of air pass the headers, flues and combustion chamber on a plurality of sides thereof, thereby absorbing the maximum amount of heat in their passage, and obtaining a maximum degree in heat exchange efficiency.

For suitably directing the heated air currents, a box-like member 49, having an open side adjacent the fan 48, may be positioned around the headers 36 and 37, flues 34 and combustion chamber 13, and may be provided at its discharge side with a plurality of adjustable deflectors 51 by which the heated air may be directed as desired.

Mounted in the distributor head 20 and extending therethrough into the combustion chamber 13 adjacent the pilot light 31, is a thermal element, indicated as a whole by the numeral 52, comprising a cylinder 53 (Fig. 3) having a shaft 54 rotatably mounted therein, the rotation of the shaft being controlled by a bi-metal ribbon 55 having one of its ends secured to the shaft 54, as indicated at 56, and its opposite end to the cylinder 53, as indicated at 57, the outer end of the shaft 54 being provided with a mercury switch 58, the arrangement of the thermal element being such that a major portion of its length is positioned within the distributor head 19 and only a small portion within the combustion chamber 13 closely adjacent the pilot light 31, it being intended that the switch 58 will be closed only when the pilot light 31 is burning, and that the operation of the thermal element will be unaffected by the operation of the burner 17, such a condition being possible by reason of the cool gas passing through the distributor head 19 and the positioning of the distributor head adjacent the air inlet openings 14 of the housing 11, thus, it will be apparent that the mercury switch 58 will be open when the pilot light is extinguished regardless of the operation of the burner 17.

Mounted, preferably, in one of the headers 36 or 37, and shown, in the present instance, as

mounted in the latter, is a thermal element 61 of a construction similar to that described with reference to the thermal element 52, the outer end of the shaft 62 of the element 61 being provided with a mercury switch 63 adapted, normally, to occupy a closed position and to open when the header becomes overheated or the temperature therein obtains a condition above normal, the switch 63 being provided with a projection or lug 64 (Fig. 5) adapted to be engaged by a resilient finger 65 when the switch is moved to open position for retaining the switch in such condition until the finger 65 is manually moved and the lug or extension 64 released.

Fig. 5 illustrates an electrical circuit for controlling the operation of the heating apparatus, and wherein a motor circuit 66 is operatively connected to the motor 45 and with a main line circuit 67 through a double-pole manually operated switch 68.

Connected in parallel with the motor circuit 66 is a circuit 69 wherein the solenoid 28 of the solenoid valve 24 and the mercury switches 58 and 63 are connected in series with each other in a manner to control the operation of the solenoid valve 24 in accordance with the condition of the pilot light 31, and in accordance with the temperature conditions existing within the header 37 with which the switch 63 is associated.

In the operation of the device, assuming that the pole switch 68 is closed, the pilot light 31 is burning and the burner 17 and motor 45 are operating normally, under which conditions, the main supply valve 26 will be open and the switches 58 and 63 will be closed as illustrated in Fig. 5. It will be apparent from the foregoing description that in the event of failure, for example, of the motor 45 to function properly, thereby interfering with the operation of the fan 47 to draw the gases of combustion from the headers 36 and 37, the overheating of the header 37 resulting from such interference will cause the switch 63 to open, thereby breaking the circuit 69, de-energizing the solenoid 28 and permitting the spring 29 to close the main supply valve 26, and thereby shut off the supply of gas to the burner 17. In the opening movement of the switch 63, the lug or projection 64 will be automatically engaged by the spring finger 65 and the switch 63 retained in open position until manually released, notwithstanding the cooling of the header 37 by reason of the discontinued operation of the burner 17.

It will be apparent also that in the event of failure of the pilot light 31 to function, the switch 58 will be moved to open position, thereby breaking the circuit 69 to de-energize the solenoid 28 and permit the main valve 26 to close and remain in such condition until the pilot is again lighted, the thermal element 52 controlling the operation of the switch 58 being unaffected by the heat within the combustion chamber produced by the burner 17 for the reasons previously described as due to the positioning of a major portion of the thermal element 52, by which the switch 58 is controlled, within the distributor head 20.

Obviously, the present invention is not limited to the precise construction and arrangement shown and described as the same may be variously modified. Moreover, all the features of the invention need not be used conjointly as the same may be used to advantage in variously different combinations and sub-combinations.

What I claim as new and desire to secure by Letters Patent is:

1. In a heating apparatus, the combination of

a combustion chamber, a plurality of flues communicating therewith and extending in opposite directions therefrom, a plurality of headers connected, respectively, to said oppositely extending flues, a casing spaced from said chamber, a plurality of conduits communicating with said casing and headers, a fan in said casing for drawing the products of combustion from said chamber into said casing and discharging them therefrom, and a second fan between said casing and combustion chamber for circulating currents of fresh air only past said headers, flues and chamber along a plurality of sides thereof.

2. In a heating apparatus, the combination of a combustion chamber, a plurality of flues communicating therewith and extending in opposite directions therefrom, a plurality of headers connected, respectively, to said oppositely extending flues, a casing having a discharge passage and spaced from said chamber, a plurality of conduits communicating with said casing and headers, a motor positioned between said casing and combustion chamber and having a shaft extending into said casing, a fan on one end of said shaft in said casing for drawing the products of combustion from said chamber into said casing and discharging them therefrom through said discharge passage, and a second fan on the opposite end of said shaft between said motor and

combustion chamber for circulating currents of air past said headers, flues and chamber.

3. In a heating apparatus, the combination of a combustion chamber, a plurality of flues communicating therewith and extending in opposite directions therefrom, a plurality of headers connected, respectively, to said oppositely extending flues, a casing having a discharge passage and spaced from said chamber, a plurality of conduits communicating with said casing and headers, a motor mounted on said conduits and positioned between said casing and combustion chamber and having a shaft extending into said casing, a fan on one end of said shaft in said casing for drawing the products of combustion from said chamber into said casing and discharging them therefrom through said discharge passage, a box-like member open at one side thereof and adapted to surround said headers, flues and combustion chamber, a second fan on the opposite end of said motor shaft adjacent the open side of said box-like member for circulating currents of air past said headers, flues and chamber and through said member, and a plurality of adjustable deflectors positioned in the side of said member opposite the open side thereof.

ARTHUR B. MODINE.
